UNITED STATES PATENT OFFICE.

WILLIAM T. NICHOLSON, OF BLACKPOOL, ENGLAND.

PACKAGE FOR BELT-HOOKS.

1,393,451.

Specification of Letters Patent.

Patented Oct. 11, 1921.

Application filed July 6, 1920. Serial No. 394,346.

To all whom it may concern:

Be it known that I, WILLIAM THOMAS NICHOLSON, subject of the King of Great Britain and Ireland, and resident of Blackpool, in the county of Lancaster, England, have invented certain Improvements in Packages for Belt-Hooks, of which the following is a specification.

This invention relates to improvements in packages for belt hooks used in joining driving belts together so that they may be readily packed and be in a position to be placed directly into the tool employed for forcing the hooks into the ends of the belts, the object 10 being to provide an improved arrangement of device by which the hooks may be spaced to the required pitch or distance apart from each other to agree with the pitch or spacing of the grooves formed in the tool which 15 is employed to hold them while being pressed into the ends of the belt.

My invention relates to the type of device comprising a sheet of paper, cardboard or the like provided with a number of slots 20 to receive the looped ends of the belt hook and consists in an improved arrangement of the paper or like sheet combined with means for holding the hooks in the spaced position until required for use.

30 My invention will be fully described with reference to the accompanying drawing in which,

Figure 1, is a side elevation of the holding means arranged in accordance with my 35 invention.

Fig. 2, developed plan of same from the inside,

Fig. 3, end elevation of the holder and 40 hooks in the finished state,

Fig. 4, rear elevation of the holder in its folded form, and

Fig. 5, section on line 5—5 of Fig. 3 but slightly enlarged showing the position of the hook within the holder.

45 In carrying out my invention I employ a sheet of paper, flexible card-board or like material *a* which in its simplest form is made sufficiently wide to correspond with a definite number of spaced belt hooks *b* and sufficiently long to pass entirely around the belt hooks so that its ends will overlap in front of the pointed portions or ends of the hooks, so as to close the space *c* between the latter. The sheet of paper *a* is provided 50 with a number of slots *d* spaced at equal

distances apart in accordance with the gage of the tool in which the hooks are subsequently placed. These slots are sufficiently long to allow the looped ends *e* of the hooks to pass through them as shown in Fig. 3, 60 so as to leave sufficient space between the inside of the loops and the outside of the paper to allow of the usual pin for holding the hooks in position in the slotted holding tool to be passed therethrough to hold them 65 in position while their pointed ends are being pressed into the ends of the belt in the well known way. The slots keep the looped ends properly spaced but in order that the arms of the hooks shall be kept in position 70 parallel to each other I secure to the sheet *a* two narrow strips of corrugated paper or other suitable material *f*, such corrugated strips allowing the hook arms to lie in the corrugations as will be seen clearly 75 from Fig. 5. As already indicated the ends of the paper *a* are overlapped as shown in Fig. 3 and are secured together by gum or other suitable mucilage so that the paper entirely surrounds the hooks. 80

The series of hooks thus held and supported can be packed for transit and always remain in the position stated. They are ready to be placed with their looped ends in the holding tool and immediately the usual 85 wire pin of the latter has been passed through the loops as aforesaid, the paper in front of the pointed ends of the hooks can be cut longitudinally or be torn away to allow of the passage of the belt end into 90 the body of the hooks. On the other hand I may secure to the inner face of one end of the paper sheet *a* a strip of strong paper *g* arranged to project at one end as shown in Figs. 2 and 4, such end enabling the paper 95 to be torn away quite easily. The projecting end of the strip *g* may be formed with a series of perforations a little distance away from the ends of the sheet *a* so allowing of easy tearing away of the paper and, if required, the sheet *a* may be provided with an integral tab instead of the projecting end of the strip *g*. 100

I would have it understood that my invention comprises the use of a single thick 105 flexible card so cut away at one surface as at *h* Fig. 1, as to leave narrow projecting portions which can have grooves formed in them similar to the corrugations of strips *f* by a suitable tool so as to act in the same 110

way as such corrugated strips. I am aware that a thin strip of metal or other suitable material provided with slots to engage the looped ends of the hooks and having corrugated portions to pass over but not in front of the hooks and held in position on this latter by a pin has previously been proposed but I do not claim such an arrangement.

What I claim and desire to secure by Letters Patent is:—

- 10 1. A package for wire belt hooks comprising a sheet of flexible material provided with a series of slots into which the looped ends of the belt hooks can be placed, separate strips of corrugated sheet material so positioned and attached to the said sheet adjacent to the said slots as to allow the corrugations to receive the arms of the hooks when the same are positioned within said 15 slots, and ends on said sheet material adapt-
20

ed to be folded around the ends of the hooks and secured to hold the hooks in position within the package.

2. A package for wire belt hooks comprising a sheet of flexible material provided at its middle part with a series of parallel slots for receiving the looped portions of the belt hooks, series of parallel guides for the arms of the hooks arranged at the ends of the said slots and operating to prevent the arms from moving sidewise, and end portions on the said sheet material adapted to be folded around the ends of the hooks and secured so as to hold the hooks in position within the package.

In testimony whereof I have hereunto set my hand in the presence of one witness.

W. T. NICHOLSON.

Witness:

MARGARET E. RAMSBOTTOM.
